UNITED STATES PATENT OFFICE

RICHARD OAKLEY KENNEDY, OF TROY, NEW YORK, ASSIGNOR TO CLUETT, PEABODY & CO., INC., OF TROY, NEW YORK, A CORPORATION OF NEW YORK

LAUNDRY IDENTIFICATION

Application filed October 6, 1931. Serial No. 567,216.

In laundering shirts and other articles it is customary for the laundries to apply identification marks and it is not unusual for different laundries to apply marks in different places on the same article. Many customers, particularly owners of fine shirts, object to the disfigurement resulting from such marking and considerable study has been given to the problem of removing this cause of complaint. So far as I am aware the only solution heretofore developed involves the use of identification labels which are temporarily attached to the articles by metal prongs or the like and which are removed after laundering; and this procedure is not only time consuming and relatively expensive but the labels sometimes become detached during the laundering process and they frequently damage the fabric.

Objects of the present invention are to provide identification means which does not disfigure the article, which need not be attached and detached each time the article is laundered, which can in nowise damage the article, and which is sufficiently simple and facile in use to discourage disfiguring methods even by less progressive laundrymen who are apparently unconcerned with the desires of their customers.

According to this invention each article is provided with a label which has, not only the usual data relating to the manufacture of the article, such as the maker's name and/or trade mark and/or the character of the material, but also a marking space, whereby a single label serves both the usual purpose and also as a carrier for the identification mark. The indicia relating to the manufacture of the article is applied to the label, preferably by weaving the indicia into the body of the label in a contrasting color, before the latter is affixed to the article by the manufacturer. In the case of custom-made articles the identification mark may also be applied by the maker but ordinarily this mark is applied by the retailer or laundry, preferably by the well-known kaumagraph process involving the use of a tape printed with indelible characters which are transferred to the label by imbibition when the tape is pressed against

the label with a hot surface. To indicate where the mark is to be applied the label is preferably provided with an indication such as the legend "Laundry mark" and/or parallel lines on one or both pairs of sides of the marking space.

For the purpose of illustration a typical embodiment of the invention is illustrated in the accompanying drawing as applied to a shirt in the usual manner, being secured to the inner face of the shirt below the neck band by stitches extending along the entire perimeter of the label, as shown by the dotted lines. The label is provided with the name "Arros", identifying the maker, the legend "Preshrunk", indicating the character of the material, the word "Trump" indicating the style of shirt, and a boxed zone for the marking with the accompanying legend "Laundry mark" further to assure the proper application of the mark by laundries receiving unmarked articles.

From the foregoing it will be evident that, by indicating the place on the label for the wearer's initials or other marking, application of the marking to the shirt or other article instead of the label is unlikely, that the location of the identification marking in a uniform place on articles sent to the laundry facilitates sorting at the laundry, that the marking may be applied to the labels in the form of stamped or woven tape or by indelible ink, either by hand or by machine, that the present disclosure is for the purpose of illustration only, and that this invention includes all modifications and equivalents which fall within the scope of the appended claims.

I claim:

1. The combination with a washable garment of a flexible label which is permanently secured to one face of the garment in spaced relation to a margin thereof, said label identifying the maker of the garment and having a space provided to receive special indelible markings identifying the owner of the garment, indicia adjoining said space to indicate its purpose, said label being capable of withstanding laundering operations.
2. The combination with a washable gar-

ment of a flexible label which identifies the maker of the garment, which has a marked zone provided to receive special indelible markings identifying the owner of the garment, which is capable of withstanding laundering operations, at least two of the opposite edges of the label being secured to one face of the garment.

3. The combination with a washable garment of a flexible label which identifies the maker of the garment, which has a space provided to receive special indelible markings identifying the owner of the garment, which is capable of withstanding laundering operations, and which is secured to one face of the garment at all portions of its perimeter.

Signed by me at Troy, New York, this
1st day of October, 1931.

RICHARD OAKLEY KENNEDY.
